UNITED STATES PATENT OFFICE.

HARRY F. TATE, OF KOKOMO, INDIANA.

INFANT'S BATH-TUB.

1,086,628.

Specification of Letters Patent. Patented Feb. 10, 1914.

Application filed July 5, 1913. Serial No. 777,563.

To all whom it may concern:

Be it known that I, HARRY F. TATE, a citizen of the United States, residing at Kokomo, in the county of Howard and State 5 of Indiana, have invented a new and useful Infant's Bath-Tub, of which the following is a specification.

The present invention appertains generally to bath tubs, and relates more particularly to an infant's bath tub.

It is the object of the present invention to provide novel and improved means for supporting an infant's bath tub in the ordinary or standard adult tub, in order that 15 the mother or attendant may conveniently bathe the child or infant.

Another object of the present invention is to provide an infant's bath tub which shall be portable in its nature, and which shall 20 be provided with adjustable brackets or hangers whereby the device may be applied to various sizes or proportions of standard tubs.

A further object of the present invention 25 is to provide means whereby the infant's tub may be supported laterally or cross wise of the standard tub, and sufficiently above the rim of the standard tub, in order that the infant's tub is readily accessible.

30 A still further object of the present invention is to provide a device of the nature indicated, which shall be comparatively simple, durable, substantial and inexpensive in construction, as well as convenient, serviceable and efficient in its use.

With the foregoing and other objects in view, which will be apparent as the nature of the invention is better understood, the present invention resides in the combination 40 and arrangement of parts and in the details of construction hereinafter described and claimed, it being understood that changes in the precise embodiment of the invention herein disclosed can be made without 45 in the scope of what is claimed without departing from the spirit of the invention.

The invention has been illustrated in its preferred embodiment in the accompanying drawing, wherein:—

50 Figure 1 is a perspective view of the improved infant's bath tub. Fig. 2 is an elevation of the infant's bath tub as applied to a standard adult tub, a portion of the infant's bath tub being broken away, and the 55 standard tub being shown in cross section.

Fig. 3 is a sectional detail. Fig. 4 is a fragmental detail of the bracket or hanger.

In carrying out the invention, there is provided an infant's bath tub 1, preferably constructed of sheet metal, and embodying the bottom 2, flat inclined sides 3 and flat inclined ends 4. The tub 1 is rectangular, and of suitable proportions for infants. It is essential that the tub be of rectangular outline, and that the end walls be inclined, 60 for the reason that the peculiar configuration of the tub will best adapt it for application to a standard tub, the flat inclined end walls being adapted to coöperate with the inclined sides of a standard tub, and the 65 flat side walls of the tub 1 being adapted to accommodate the hangers hereinafter described, in order that the tub 1 may be properly and effectively supported from the rim of a standard tub. The tub 1 need not be 70 fashioned from sheet metal, but may be in the form of a casting, as long as the tub possesses sufficient inherent rigidity for resisting the strains to which it may be subjected. The ends 4 are preferably extended 75 upward, as at 5, above the sides 3, which will prevent the water within the tub 1, from splashing over the ends. The upper edges of the sides and ends are preferably beaded, 80 for the purpose of strength and protection. 85 The tub 1 is preferably enameled or otherwise finished for reasons which will be manifest.

The bottom 2 of the tub is provided with the drain opening 6 at one of the rear corners, and a suitable stopper or plug 7 is adapted to be engaged downwardly within the opening 6 to normally close the same. A chain or flexible element 8 is attached to the bottom of the stopper 7, in order that it may 90 be disposed on the exterior of the tub, instead of the interior, the other end of the chain 8 being attached to the respective side 95 3 of the tub. Thus, the chain 8 will be on the exterior, and will not interfere with the infant, and furthermore, the plug 7 being disposed at the rear end of the tub, will be out of reach of the infant, in order that the infant may not accidentally remove the 100 stopper or plug 7, so as to discharge the 105 water or contents of the tub. When the stopper 7 is removed from the opening 6, it will be observed that the chain 8 is adapted to pass upwardly through the opening 6, and will prevent the stopper from being 110

lost or mislaid and the chain 8 will also assist in pulling the stopper into the opening 6, the chain being out of the infant's reach, and not being liable to catch the wash cloth, 5 as might be the case if the chain were disposed upon the interior of the tub.

An adjustable bracket or hanger 9 is provided for each end of the tub, each of the hangers being bent from a rod 10, or other 10 suitable stock. The rod 10 has its end portions bent angularly to provide the arms 11, the intermediate portion of the rod forming a yoke 12 connecting the outer ends of the arms 11. It will thus be observed that each 15 of the hangers is of U-shape to surround the respective end of the tub 1. The outer ends of the arms 11 are bent downwardly slightly, as at 13, in order that the yoke 12 will hang slightly below the plane of the 20 arms 11, the curved portions 13 being covered by resilient tubular facings 14, preferably of rubber hose or the like. The remaining portions of the arms 11 are straight. The arms 11 of the hangers are slidably engaged to the sides of the tub, the yokes 12 extending across the ends of the tub. In order to slidably engage the arms 11 to the sides of the tub, keepers 15 are secured to the sides of the tub adjoining the ends. 25 Each of the keepers 15 embodies a sheet metal plate 16 having its edges riveted to the sides of the tub, and provided with a longitudinal outstruck corrugation 17 to receive the straight portion of the respective 30 arm 11. It is to be understood, however, that the keepers may be fashioned in any equivalent manner. The inner ends of the arms 11 of the hangers are slid inwardly through the respective keepers 15, in order 35 that the hangers will be slidably carried by the end portions of the tub, the yokes 12 being adapted to move to and from the ends of the tub. It is to be understood that the hangers may also be removed or withdrawn 40 from the keepers, whenever desired.

In applying the present attachment to a standard adult tub, the hangers are properly adjusted so as to accommodate the particular width of the standard tub, and the infant's bath tub 1 is then placed laterally or cross wise within the standard tub, as illustrated in Fig. 2. The curved portions 13 of the arms 11 are adapted to contact with the rim of the standard tub, the tubular facings 50 14 engaging the rim of the standard tub, to prevent the same from being scratched, marred or otherwise injured, and to also prevent the tub 1 from sliding longitudinally of the standard tub. When the infant's bath 55 tub is thus applied to the standard tub, it will be apparent that the infant's bath tub will project above the standard tub, in order that the tub 1 will be readily accessible. By adjusting the respective hangers 9, the tub 1 60 may also be moved endwise between the sides

of the tub, in order that the tub 1 may be disposed close to the side of the standard tub at which the mother or attendant stands. The ends of the tub 1 being raised, will somewhat eliminate the water from splashing 70 from the tub 1, over the sides of the standard tub, the front end being curved outwardly above the sides 3, as seen in Fig. 2, in order that there will be no obstruction in the way of the mother or attendant. Any water 75 splashing over the sides of the infant's bath tub will fall into the standard tub. Water may be readily poured or run into the infant's bath tub, and after the infant or child has been bathed, the water may be drained 80 from the tub 1, by raising the stopper 7. After the infant's bath tub has been used, the same may be lifted readily from the standard tub, and the hangers may be slid inwardly in order that the infant's bath tub 85 may be compactly stored or carried. It is also to be observed that the hangers may serve as handles, for carrying the infant's tub. The arms 11 of the hangers 12 work snugly through the corrugations 17 of the 90 keepers, so as to frictionally hold the hangers at any position to which they are set, it being noted that the curved portions 13 of the arms 11 in engaging over the rim of the standard tub, will prevent the present device 95 from shifting laterally on the standard tub.

Particular attention is directed to the fact that the flat inclined ends of the infant's tub may fit snugly against the sides of the standard tub, it thus being possible to set the infant's tub within certain standard tubs, without the employment of the hangers, when desired. The raised ends of the infant's tub are also of advantage in preventing the water from running or splashing 100 over the ends, which ends are engaged to or disposed snugly adjoining the sides of the standard tub. Should the water level within the infant's tub rise excessively, the water would flow over the sides of the infant's 105 tub and directly into the standard tub. It is also to be noted that the keepers 16 will not obstruct the ends of the infant's tub, or the bottom thereof, which will enable the infant's tub to be set on the floor, or other surface, when desired, and which will also permit the infant's tub to be placed within the standard tub without the hangers, and without the ends of the infant's tub being 110 encumbered.

Having thus described the invention, what is claimed as new is:—

In a device of the character described, an infant's tub of rectangular outline, adapted to be disposed transversely between the sides 115 of a standard tub, the end walls of the infant's tub being flat and inclined, whereby the said ends may fit snugly against the sides of the standard tub, the end walls of the infant's tub extending above the side walls, 120 125 130

keepers secured to the side walls of the infant's tub adjoining the end walls, and U-shaped hangers adapted to surround the ends of the infant's tub and to rest on the 5 rim of the standard tub, the arms of the hangers being receivable by the keepers.

In testimony that I claim the foregoing as

my own, I have hereto affixed my signature in the presence of two witnesses.

HARRY F. TATE.
